UNITED STATES PATENT OFFICE.

CHARLES G. WEYGANDT, OF HYNDMAN, PENNSYLVANIA.

RAIL-JOINT.

No. 914,210.

Specification of Letters Patent.

Patented March 2, 1909.

Application filed May 2, 1908. Serial No. 480,593.

To all whom it may concern:

Be it known that I, CHARLES G. WEYGANDT, a citizen of the United States, residing at Hyndman, in the county of Bedford and State of Pennsylvania, have invented new and useful Improvements in Rail-Joints, of which the following is a specification.

This invention relates to rail joints, the object of the invention being to provide a practical and thoroughly reliable truss joint adapted for the rail support and brace of the abutting ends of railroad rails where the joint occurs for example, between adjacent ties instead of directly over or upon a tie.

With the above and other objects in view, the invention consists in the novel construction, combination and arrangement of parts as herein fully described, illustrated and claimed.

In the accompanying drawings:—Figure 1 is a side elevation of a rail joint embodying the present invention. Fig. 2 is a vertical cross section through the same taken on the line 2—2 of Fig. 1. Fig. 3 is a similar section on the line 3—3 of Fig. 1.

Referring to the drawings, 1 designates a series of ties and 2 and 3 designate the rail ends which meet or approach each other at the joint 4.

In carrying out the present invention, I provide a pair of oppositely arranged splice bars 5 which also constitute supporting chairs for the rail ends, the said splice bars being provided with bottom flanges 6 which extend beneath the base of the rail as clearly shown in Fig. 2. Each of the splice bars is substantially triangular in vertical cross section as shown in Fig. 2 and at opposite sides of the joint 4 and located equidistantly therefrom each splice bar is provided with outwardly projecting lugs 7 each of which is provided with an inclined groove or seat 8 for the reception of the two members or sections 9 and 10 of a truss rod.

The adjacent end of the truss rod sections are provided with right and left hand screw threads as shown at 11 with which a turn buckle 12 engages for connecting said sections and placing the same under the necessary tension to form a rail support and truss for the rail joint. While the inner portions of the truss rod sections are disposed hori-

zontally, as shown in Fig. 1, the outer end portions thereof are inclined upwardly as shown in the same figure and said sections 55 terminate at their outer ends in enlargements 13 in the form of flat plates which bear against the web portions of the rail ends as shown in Figs. 1 and 2. These end portions or plates are secured to the rail ends by inserting bolts 14 therethrough as best illustrated in Figs. 1 and 3, thus tying the rail ends together and placing the truss rods at opposite sides of the rail joint under the necessary tension to form the requisite support 65 and brace for the joint as a whole. The splice bars are designed to be secured to the ties upon which they rest by means of the ordinary spikes 15.

I claim:—

1. The combination with rail ends, of splice bars overlapping said ends and arranged at opposite sides of the rail, said splice bars being provided with grooved seats and truss rods secured to the rail ends 75 and engaging said seats and provided with turn buckles, substantially as described.

2. The combination with abutting rail ends, of splice bars arranged at opposite sides thereof and extending across the joints 80 between the rail ends, said splice bars being provided with grooved seats, and truss rods arranged at opposite sides of the rail and having their outer ends fastened to the rails, each truss rod comprising sections engaging 85 said seats and having right and left hand screw threads, and a turn buckle connecting the threaded ends of the sections.

3. The combination of abutting rail ends, of splice bars located at opposite sides there- 90 of and provided with inclined seats, and truss rods located at opposite sides of the joint and having their opposite ends secured to the rails, each truss rod embodying sections hav- 95 ing inclined portions which engage said seats, and right and left hand threaded portions, and a turn buckle connecting said threaded portions.

In testimony whereof I affix my signature in presence of two witnesses.

CHARLES G. WEYGANDT.
